CATHODE-RAY TUBE SCREEN TREATMENT

Arthur L. Samuel, Poughkeepsie, N. Y., assignor
to International Business Machines Corpora-
tion, New York, N. Y., a corporation of New
York

Application June 19, 1951, Serial No. 232,311

10 Claims. (Cl. 316—1)

1

This invention relates generally to a process for the treatment of cathode ray tube screens and more particularly to such a process for treating cathode ray tube screens to remove imperfections and produce uniformity of the screen.

The requirement for digital computing machines of large storage capacity has led to the development of storage systems in which the digits are represented by a charge pattern on the screen of a cathode ray tube. For this purpose conventional cathode ray tubes are employed in conjunction with a "signal" or "pick-up" plate, consisting of a sheet of metal foil or gauze external to the tube and closely attached to the face thereof. Each elemental area of the screen is therefore capacity coupled into a common channel, as in the iconoscope.

A major drawback to the use of this system, however, is that cathode ray tube screens produced even by the best manufacturing methods known in the past invariably have one or more imperfections which cause errors if the portion of the screen where the imperfection occurs is utilized for storage purposes. This has been recognized in the art, and various solutions have been suggested. Each of these solutions, however, has been in the nature of a compromise, such as utilizing a lower accelerating voltage for the tube than is otherwise deemed desirable or blanking electronically the imperfect portion of the screen utilized in the particular installation. The magnitude of the problem is apparent when it is realized that even with these compromising methods only from 10% to 50% of the cathode ray tubes commercially produced are usable for storage systems, and the remainder must be discarded either because of the number of imperfections on the screen of each tube or the large size of one or more of these imperfections on a particular tube.

The principal feature of this invention is the provision of a process for the treatment of cathode ray tube screens which will remove these imperfections and produce uniformity of the screen.

The invention will be best understood from the following description and drawings which disclose, by way of example, the principle of the invention and the best mode, which has been contemplated, of applying that principle.

In the drawings:

Fig. 1 shows diagrammatically a circuit arrangement for testing a cathode ray tube screen for imperfections; and

Fig. 2 shows a Tesla coil circuit of the type utilized in the treatment of cathode ray tube screens according to the invention.

As shown in Fig. 1, each cathode ray tube 10 is connected to an energization and vertical sweep circuit 12 which energizes the tube electrodes and causes its electron beam to sweep its screen 14 in

the vertical direction. A foil or conducting coating 16 is positioned on the face of the tube adjacent the screen 14 as shown and is connected to the input of amplifier 18. The output of amplifier 18 is connected to the "Z" axis or intensity control circuit of oscilloscope 20, whose horizontal sweep circuits are connected to the horizontal deflecting elements of tube 10 as indicated. The vertical sweep circuits of circuits 12 are also connected to the "Y" axis or vertical deflecting elements of oscilloscope 20, and thus the time base sweeps of tube 10 and oscilloscope 20 are in synchronism. The resultant scan on each is of the line-by-line type, but any desired form of scanning may be employed: e. g., spiral, interlaced, etc. In one embodiment, a 1 kc. horizontal sweep was employed with a 2 c. p. s. vertical sweep.

Alternatively, instead of providing a raster 20 scanning the entire face of tube 10 in synchronism with the scanning of oscilloscope 20, a positioning voltage, manually controllable, might be applied to the "Y" axis input of oscilloscope 20 and to the vertical deflecting elements of tube 10 instead of utilizing the vertical sweep circuit disclosed. Thus, merely a single line trace would appear on the face of tube 10 together with a corresponding single line trace on the indicator of oscilloscope 20, both traces being movable in synchronism up or down manually by adjustment of the positioning control.

At each portion of the screen 14 that the electron beam encounters an imperfection (or in other words, wherever the secondary emission ratio is more or less than that of the majority of the screen), the input to the amplifier 18 will be altered, resulting in an alteration of the intensity of the electron stream in the cathode ray tube of the oscilloscope 20. As a result, visible indications 40 of the imperfections of the secondary emissive surface or screen 14 of the cathode ray tube 10 will be determined.

These imperfections, which would render the tube unusable for storage purposes, as outlined above, may be removed in accordance with this invention by removing the foil 16 from the face of tube 10 and moving a probe connected to the high frequency high voltage output of Tesla coil over the face of the tube adjacent the portions 50 where the imperfections have been detected, as described above. Usually only one passage of the probe is required over the tube face adjacent each imperfection. The electrostatic charge remaining on the tube 10 must, of course, thereafter be removed. Preferably foil 16 is then replaced and the entire screen 14 of the cathode ray tube 10 reexamined by means of the circuit arrangement shown in Fig. 1 in order to determine that the imperfections have been removed and a uniform screen produced.

One convenient form of Tesla coil utilized has been the commercial Central Scientific Co. Catalogue No. 80730 "High Frequency Coil of the Tesla Type." It is understood that the circuit of this is of the type shown in Fig. 2, which is given merely by way of example, and that it produces an output of approximately 35 kv. The primary coil of transformer 30 is supplied with 110 v. 60 cycle A. C. and the turns ratio of this transformer is such that approximately 5,000 volts is produced across the secondary thereof. This high voltage is applied to a tank circuit 32 and adjustable air gap 35 in series. Tank circuit 32 includes an inductance 33 and a condenser 34 connected in parallel with their parameters chosen such that the tank circuit 32 is resonant at approximately 500 kc. One terminal of the secondary of transformer 30 is also grounded as shown. The other terminal is connected through isolating condenser 36 to probe 37, which is applied to the face of the cathode ray tube 10, as necessary, as described above. The high alternating voltage applied across air gap 35 causes the air dielectric in the gap to break down, each time the sine wave exceeds a certain value as determined by the dimension of the gap. This breaking down of the air in the gap produces a "ringing" or oscillation of the tank circuit 32 at its resonant frequency, thereby producing bursts of high frequency energy at probe 37. Isolating condenser 36 effectively isolates probe 37 from the A. C. power voltage but presents a negligible impedance to the high frequency energy.

While the process described above included only treatment of selected portions or areas of the cathode ray tube screen 14, i. e., those which were found to be imperfect as demonstrated by the circuit arrangement in Fig. 1, it is of course, apparent that the entire screen 14 may be so treated by applying probe 37 to the face of tube 10, either elemental area by elemental area, or all at once by connecting foil 16 to probe 37 instead of to the input of amplifier 18.

The disclosed process for treatment of cathode ray tube screens has been demonstrated to be most effective, and it has been found that the majority of the commercially available cathode ray tubes which were otherwise unfit for use in storage systems of the type described above prior to treatment by this process had their imperfections removed and the screens rendered uniform after a single application of high frequency energy from a Tesla coil over the face of the tube.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. The process of treating the screen of a cathode ray tube to remove imperfections and

produce uniformity thereof which comprises applying to the outer face of the tube a high voltage of alternating polarity.

2. The process of treating the screen of a cathode ray tube to remove imperfections and produce uniformity thereof which comprises applying to the outer face of the tube a high frequency voltage.

3. The process of treating the screen of a cathode ray tube to remove imperfections and produce uniformity thereof which comprises applying to successive elemental areas of the outer face of the tube a high voltage of alternating polarity.

4. The process of treating the screen of a cathode ray tube to remove imperfections and produce uniformity thereof which comprises applying to the outer face of the tube a high voltage of high frequency.

5. The process of treating the screen of a cathode ray tube to remove imperfections and produce uniformity thereof which comprises applying to the outer face of the tube an alternating voltage of the order of several thousand volts.

6. The process of treating the screen of a cathode ray tube which comprises applying to the outer face of the tube a high frequency Tesla coil output.

7. The process of testing and treating the screen of a cathode ray tube which comprises scanning said screen elemental area by elemental area to determine imperfect portions thereof and thereafter applying an alternating voltage to the face of the tube adjacent the imperfect portions thus found to remove the imperfections.

8. The process of testing and treating the screen of a cathode ray tube which comprises scanning said screen elemental area by elemental area to determine imperfect portions thereof and thereafter applying a high voltage of alternating polarity to the face of the tube adjacent the imperfect portions thus found to remove the imperfections.

9. The process of testing and treating the screen of a cathode ray tube which comprises scanning said screen elemental area by elemental area to determine imperfect portions thereof and thereafter applying a high frequency voltage to the face of the tube adjacent the imperfect portions thus found to remove the imperfections.

10. The process of testing and treating the screen of a cathode ray tube which comprises scanning said screen elemental area by elemental area to determine imperfect portions thereof and thereafter applying a high voltage of high frequency to the face of the tube adjacent the imperfect portions thus found to remove the imperfections.

ARTHUR L. SAMUEL.
